UNITED STATES PATENT OFFICE.

REUBEN A. BOGLEY, OF WASHINGTON, DISTRICT OF COLUMBIA.

HAT HOLDER.

Application filed February 18, 1922. Serial No. 537,634.

To all whom it may concern:

Be it known that I, REUBEN A. BOGLEY, a citizen of the United States, residing at Washington, in the District of Columbia, have invented certain new and useful Improvements in Hat Holders; and I do hereby declare the following to be a full, clear, and exact description of the invention, such as will enable others skilled in the art to 10 which it appertains to make and use the same.

This invention relates to detachable devices for holding a hat in place upon a supporting surface and is particularly adapted 15 for use on the bottom of a trunk tray, or the like, lined with any suitable fabric or coated with a suitable finish.

An object of the invention is to enable a hat holder to be attached securely to the 20 bottom of the tray or other foundation in such manner as to avoid chafing and wearing through the fabric lining thereof, or marring the surface finish during the act of attaching or detaching the holding device, or to prevent wear due to any relative 25 movement that may occur between the hat holder and the tray or other foundation.

A further object is to avoid all inconvenient projections in the trunk tray or the like 30 when the hat holding device is removed and not in use.

The invention consists in the combination of a foundation, such as the bottom of a trunk tray, and a hat holder, comprising 35 a base member, detachably secured to said foundation and spaced therefrom so that the edges of the base member are maintained out of contact with the surface of said foundation. It also consists in the 40 combinations, sub-combinations and details of construction more specifically described hereinafter, illustrated in the drawings and defined in the appended claims.

In the accompanying drawings in which 45 like reference characters designate like parts throughout the several views:

Figure 1 is a perspective view of a fragment of the bottom of a trunk tray having a hat holder secured thereto;

Figure 2 is a section through a fragment 50 of the bottom of a tray and through a hat holder detachably secured thereto embodying one form of my invention;

Figure 3 is a similar section embodying 55 a slight modification of the invention;

Figures 4, 5 and 6 are similar sections showing still other modifications of the invention, and

Figure 7 illustrates a form of bolt and washer suitable for use in carrying out the 60 invention.

The invention will be described in its application to trunk trays but is not to be limited to such application.

Trunk trays are commonly made of wood 65 veneer lined with linen, other suitable fabric, or paper linings; or they may be of more or less expensive wood having a fine finish applied to the surface. Hat holders of a type comprising a base member of generally 70 circular form, on which is secured a rounded cushion adapted to be penetrated by a hat pin, are frequently attached within the trays to hold a hat in place so that it may not slip around and become injured during 75 transportation. It is desirable that holders of this and other types be made attachable and detachable and it is of course also desirable that when the hat holder is detached there be no protuberances left in the tray 80 which will interfere in any way with other uses to which it may be desired to place the tray. It is also desirable that the hat holder may be secured to or detached from the bottom or sides of the trunk or tray 85 without marring the lining or other finish covering the surface. In patent to Wright and Topham No. 782,096, patented February 7, 1905, there is disclosed a hat holder of the general type to which the present 90 invention applies, shown adapted to be detachably connected to the bottom of a trunk tray and when removed therefrom to leave no projecting members in the tray. In the device of said patent the base piece of the 95 hat holder is secured firmly in contact with the upper surface of the tray bottom. It has been found that in the acts of attaching and detaching the holder of this patent to the bottom of the tray or similar supporting surface the friction between the 100 relatively moving base member and the foundation surface in securing and releasing the holder soon wears away the fabric or other finish on the bottom of the tray 105 or other surface. In my invention the hat holding device may be attached and detached any number of times without any danger of marring the lining or other 110 finish.

In the drawings forming part of this specification, 1 indicates the base of a trunk tray or other foundation to which a hat holder is detachably secured. The upper surface of the foundation 1 is shown covered with a lining 2 of linen, or the like, or a coat of fine varnish or other finish. A generally circular base plate 3 constitutes the bottom of a hat holding device upon which is formed a cushion 4 composed of hair or any other suitable stuffing material encased within a fabric covering, the edges of which may be tacked to the edge of the base plate 3 and covered with tape or other border as indicated at 5. In the embodiment of the invention shown a T-headed bolt is passed through the center of the base member 3 from its inner side 3^a so that the preferably threaded shank 7 thereof protrudes from beneath or from the outer side 3^b of said base. Said T-headed bolt is provided with spurs 8 adapted to be driven into the wood or other material of which the base 3 is constructed so as to hold said bolt from rotating with respect to base 3. A means is provided on the foundation or tray bottom 1 to engage the shank 7 of the bolt in such manner as to secure the hat holding device to the foundation. This means may be in the foundation itself or in an anchoring device secured to the foundation.

In order that no part of the base 3 may contact with the foundation surface when the hat holder is in place or being secured or detached suitable spacing means is disposed between them.

As a convenient means of engaging the bolt shank 7 with the foundation 1 may thread said shank as indicated in the drawings and form a correspondingly threaded opening in the foundation or in an anchoring member secured thereto. And the outer or under side of the base 3 may be suitably spaced from the adjacent surface of the foundation by limited raised surfaces on the foundation, surrounding the opening therein, or on the outer or under surface of the base 3 surrounding the shank 7, or on both; or the two surfaces may be spaced by a separate washer surrounding said shank. The spacing may be effected by a raised anchoring device, secured to the foundation or by a raised nut or washer secured to the under side of the base.

In Figure 2 I have shown an anchoring member 9 on the base serving also as a spacing means. Said anchoring member may be a plate having a central threaded orifice adapted to engage corresponding threads on the shank 7. This anchoring member 9 may be riveted, screwed or tacked to the foundation 1 and project slightly above its surface as indicated. Thus, when the hat holder is adjusted to the base 1 by screwing the shank 7 into the threaded opening of the anchoring

member 9 it will be spaced from the lining or other surfacing on the foundation 1 so that in rotating said hat holder in one direction to secure it to the foundation, or in the other direction to detach it therefrom, the under surface of the base will not rub upon the surface 2 and mar it.

Preferably, also a plate, nut or washer 10 may be secured to the under surface of the base 3 which may aid in holding the bolt securely in place and provide a suitable hard surface to contact with the surface of anchor plate 9 or other spacing member, and said member 10 may have its under surface flush with the under surface of base 3 or raised from it.

It will be apparent that the under surface of the base 3 of the hat holder may be spaced from the foundation 1 by many different means. For example, in Figure 3 there is shown an anchoring member 9^a sunk flush with the surface of the foundation 1 and a disk-like spacing member 10 secured to the base 3 around shank 7 and raised from the under surface of the base. In this form of the invention when the hat holder is being screwed to place the spacing member 10 will contact with the flush surface of the anchoring member 9^a and thus space the base 3 from the surface 2 of the foundation 1. In this form when the hat holder is removed there remains a flush surface so that clothing or other articles will not be caught or interfered with by any protuberance on the bottom of the tray or other foundation.

The spacing means may be a loose washer, as shown at 11 in Figure 6, one face of which engages the upper face of the anchoring member 9^a and the other the under surface of base 3 or the plate 10 secured thereto.

Instead of having the anchoring member flush with the upper surface of the tray or other foundation but yet serve as a spacing means and offer no corners to catch on clothing or the like, the said anchoring member may be made convex, as indicated in Figure 4 at 9^b. The anchoring member 9^b may be riveted or otherwise secured to the tray bottom or other foundation 1 so as to present a slight convex protuberance having a central threaded opening into which the shank 7 projecting from the base 3 may be screwed. In this as in all cases, if desired, a suitable wear plate, as indicated at 10^a, may be fastened to the under side of the base 3 surrounding the shank 7.

As shown in Figure 5 a convex spacing plate 9^c may be secured to the under side of the base 3 instead of to the upper side of the foundation 1, shank 7 of the bolt being screwed into an anchor plate 9^a made flush with the upper surface of said foundation. It will also be apparent that a convex spacing plate like 9^b and 9^c may be used as a

loose washer or threaded nut surrounding the shank 7 of the bolt, as shown in Figure 7 at 9^d, in order to space the base 3 from the upper surface of the foundation member 1, 5 and that this convex washer or nut 9^d may be placed either side up; that it may be used in connection with any suitable flush anchoring device 9^a and with or without the wear plate 10, 10^a secured to the under side 10 of the base 3.

By means of this improvement a hat holder of the type described may be attached to and detached from the bottom of a trunk tray or other foundation or support without any danger of wearing through the lining or marring the finished surface.

Having described my invention in such manner as to enable those skilled in the art

to make and use the same, what I claim and desire to secure by Letters Patent is:

In a device of the class described, the combination of a foundation, a hat holder comprising a base plate, a threaded shank extending through said plate, means on the inner end of said shank for engagement 20 with said plate, an anchoring plate and a spacing plate, said plates being provided with centrally disposed registering threaded openings and being adapted to cooperate with said threaded shank, said anchoring 25 plate being provided with an inverted dished body portion, whereby the hat holder will be spaced from the foundation.

In testimony whereof I affix my signature.

REUBEN A. BOGLEY.
